UNITED STATES PATENT OFFICE.

SAMUEL JOHN HOLTHAM, OF NEW TORONTO, ONTARIO, CANADA, ASSIGNOR TO
JOSEPH S. A. WHEALY, OF TORONTO, CANADA.

PAPER-BAG-PRINTING MACHINE.

1,368,258.

Specification of Letters Patent. Patented Feb. 15, 1921.

Application filed November 22, 1919. Serial No. 389,840.

To all whom it may concern:

Be it known that I, SAMUEL JOHN HOLTHAM, residing at New Toronto, in the county of York, in the Province of Ontario, 5 Canada, have invented certain new and useful Improvements in Paper-Bag-Printing Machines, of which the following is the specification.

My invention relates to improvements in 10 paper bag printing machines and the object of the invention is to devise simple means which may be adjusted to print any desired advertising matter upon the paper as it is fed to the bag making machine and which 15 may be readily adjusted so as to place such advertising matter in any desired location upon the paper according to the size of the bag which is formed from the paper by the bag machine, and also to provide means 20 whereby the inking rolls may be readily separated so as to be set out of contact one with the other when idle and thus prevent their deformation and further to provide means whereby a thorough distribution of 25 the ink upon the type is effected and it consists essentially of the arrangement and construction of parts as hereinafter more particularly explained.

Figure 1 is a plan view of my paper bag 30 printing machine.

Fig. 2 is a longitudinal section through Fig. 1.

Fig. 3 is a side elevation of my machine.

Fig. 4 is an enlarged perspective detail of 35 the means for clamping the type to the cylinder.

Fig. 5 is a detail showing the means for spacing the final inking rolls from the type.

Fig. 6 is a fragmentary plan view.

40 In the drawings like characters of reference indicate various parts in each figure.

1 indicates the main frame of my machine, the right hand portion of which is provided with upwardly extending bearing 45 portions 2 and 3. 4 and 5 are slideways in which are supported bearing blocks 6 and 7. 8 is a shaft which is journaled in the bearing blocks 6 and 7. 9 is my type cylinder which is provided with hubs 10 through 50 which extend securing screws 11 for securing the type cylinder to the shaft 8. The type cylinder 9 is provided with a series of longitudinal grooves 12 which are preferably six in number, and are arranged an 55 even distance apart.

13 indicates my type plate which is segmental cylindrical in form and is provided at its ends with bevel portions 14 and 15. 16 and 17 are blocks which are slidably held in the groove 12, the end walls of the 60 grooves being formed by plates 9'. 18 are adjusting screws.

As will be seen by referring to Fig. 4, each adjusting screw is provided with an annular groove 19 located in that portion 65 of the screw extending through the end wall of the groove 12. 20 is a holding pin which extends downward from the outer periphery of the plate 9' into the groove 19. 21 is a knob secured to the outer end of each 70 screw 18 and by which the screw may be turned by the operator. Each screw 18 extends through a pair of blocks 16 and 17 so as to engage therewith. The inner end of each block 16 and 17 is provided with a 75 notch 23 which engages the beveled ends of the type plate 13. The threads at the ends of the screws 18 are reversely set and by turning the screw 18 it will be readily seen that the blocks are withdrawn. The 80 type plate may be either withdrawn for renewal or adjusted circumferentially to any desired extent.

It will be readily understood that when 85 large bags are being made up on the bag machine it would only be necessary to use one type plate 13, the impression being made upon the paper once in every revolution of the type cylinder, the paper required being equal in length to the circumference of the 90 cylinder.

When small sized bags are to be made by the bag machine, that is to say, a bag half the length of the larger size, it will be necessary to have two impressions during each 95 revolution of the type cylinder and for this condition I provide two type plates 13 as indicated in the drawings. If it is desired to print upon a bag one-third the size of the larger size, then the type plates 13 shown in the drawings are adjusted to the required position and an extra type plate inserted so that three type plates are spaced at an equal distance around the type cylinder.

24 is an impression roll which is mounted 105 upon a shaft 25 journaled in suitable bearings in the portions 2 and 3 of the main frame. The impression roll 24 is provided with a suitable padding of paper 26 so as to give the required resistance to the type 110

when brought into contact therewith, 27 is a guiding roller which is journaled in bearings 28 also carried by the bearing portions 2 and 3 of the main frame. 29 is a magazine roll upon which the supply of paper is wound. Adjacent to the magazine roll is mounted a guiding roller 30 on standards 31. The paper 32 passes from the magazine 29 over the guiding roller 30 around the 10 guiding roller 27 and over and around the roll 24 so as to pass between the impression roll and the type cylinder and from beneath the impression roll onward to the bag machine. The shaft 25 upon which the impression roll 24 is mounted forms the main driving shaft of the machine, this shaft being driven from any suitable source of power. Upon one end of the shaft 25 is mounted a gear 33. 34 is a gear secured to 15 the shaft 8 of the type cylinder. 36 are collars secured to the shaft 8 in proximity to each end thereof, for a purpose which will hereinafter appear.

35 is the inking fountain of the machine. 25 The fountain 35 comprises a base member 35^x which is slidably supported in a suitable slideway 37 formed in the main frame 1 of the machine. 38 and 39 are bearing standards which are provided with foot portions 30 40 having slots 41 therein through which extend securing screws 42 for adjustably securing the standards to the member 35^x. 43 is an inclined inking plate upon which the supply of ink is held. 44 is the main inking 35 roll. 45 is the ink transferring roll. 46 and 47 are ink transferring and distributing rolls which co-act with the intermediate roll 48. Bearing upon the periphery of the roll 47 are rolls 49 and 50 which transfer 40 the ink finally on to the type 13 of the type cylinder 9. 49^x and 50^x are the spindles of the type rolls inking 49 and 50. The spindles 49^x and 50^x project beyond the rolls 49 and 50 as indicated in Fig. 1 and are journaled in bars 52 which are pivotally supported intermediate of their length on pins 53 carried by the swinging bars 54 each of which is mounted upon a pin 55 carried in the main frame of the machine. In order to 50 space the rolls 49 and 50 the exact distance from the type cylinder required so that the periphery thereof just touches the type as they revolve I have provided the spindles 49^x and 50^x with rollers 56 and 57 in contact 55 with the collars 36 thereby definitely spacing the rolls 49 and 50 in position from the type cylinder.

The roll 48 is mounted upon a spindle 58 which projects beyond the end of the roll 60 and is journaled in arms 59 and 60. The lower ends of the arms 59 and 60 are pivotally mounted in plates 61 and 62 carried by the standards 38 and 39 of the inking fountain. When the roller 48 is not in use it is 65 swung upward into the dotted position in-

dicated in Fig. 2 so as to be out of contact with the ink distributing rolls 46 and 47. It has been found that where the inking rolls are left in contact that owing to their being formed of relatively soft material 70 they will gradually become deformed by their own weight bearing against one another. For this reason it is desirable when the rolls are not in use to hold them in a separated position.

In order to separate the ink distributing roll 47 from the rolls 49 and 50 all that it is necessary to do is to slide the ink fountain outward upon the slide ways 37. By this movement the transferring roll 47 is carried out of contact with the rolls 49 and 50 and the rolls 49 and 50 then drop downward out of contact with the type by gravity with the bars 54 on which they are carried.

I will now describe the means by which the ink is distributed longitudinally of the inking rolls. The distributing ink rolls 46 and 47 are mounted on spindles 63 and 64 which are free to move longitudinally in 90 their bearings located in the standards 38 and 39. The distributing ink rolls 46 and 47 are reciprocated longitudinally in opposite directions by the following mechanism. 65 and 66 are grooved wheels secured 95 to the spindles 63 and 64. 67 is a standard bracket supported on one side of the machine and in which is supported a vertical rocking shaft 68. 69 is a cross arm carried by the upper end of the shaft 68 provided at 100 the ends with fork members 70 and 71 the forks of which enter the grooves of the wheels 65 and 66. The stem of the members 70 and 71 are turnably held at their lower ends in the cross arm 69. The lower 105 end of the rocking shaft 68 is provided with an arm 72 extending outward therefrom. 73 and 74 are gear wheels mounted upon spindles 63 and 64. 75 is a broad gear pinion mounted upon the stud 76 and in mesh 110 with the gears 73 and 74. The pinion 75 is driven from the gear wheel 34 by means of a gear wheel 77 mounted upon the short shaft 78. The short shaft 78 is journaled in a bearing 80 carried on the side of the 115 machine and is provided at its opposite end with a gear wheel 82 which is provided with a crank pin 83 connected by a link 84 to the outer end of the arm 72. 85 is a gear mounted upon a swinging bracket 86 secured to 120 the side of the machine by a bolt 87. The gear 85 is in mesh with the gear 82 and gear 34 thereby completing the driving connection which is formed from the gear 34 through the gears 85 and 82 and shaft 125 78 connected to the gears 73 and 74 by the gear 77 secured to the opposite end of the shaft 78 and by the broad gear pinion 75 which is constantly in gear with the gears 73 and 74 carried by the spindles 63 and 130

64 which are reciprocated longitudinally in opposite directions, the reciprocating action being provided for by means of the crank pin 83 and link 84 imparting a swinging movement to the arm 72. By this means the forks 70 and 71 are carried in opposite directions carrying the inking rolls 46 and 47 in a corresponding direction while in contact with the distributing ink rolls 48 and 49 and 50. This reciprocating action of the rolls 46 and 47 is to effect the spreading of the ink carried thereby longitudinally while revolving in contact with the rolls 48 and 49 and 50.

88 is a shaft journaled in the bearing standards 38 and 39. 89 are arms secured to the shaft 88 at each end thereof. 90 is a ratchet wheel carried by the spindle of the main ink roll 44. 91 is a bar swung upon the spindle of the main ink roll 44. 92 is a link connecting the lower end of the bar 91 to the gear 77 eccentrically thereof. 93 is a pawl carried by the upper end of the bar 91 in engagement with the ratchet wheel 90. 94 is a detent carried by the shaft 88 and adapted to engage with the edge of the bar 91 when the lower end of the bar is swung toward the type cylinder. When the bar 91 is swung in this direction after the rotary movement of the main inking roll the ink transferring roll 45 is carried into contact with the main ink roll against the tension of the spring 95. As soon as the bar 91 moves in the opposite direction the detent 94 is released and the spring 95 acts to carry the ink transferring roll 45 into contact with the ink distributing roll 46.

It will thus be seen from this description that I have provided a machine whereby

suitable advertising matter may be printed on a bag of any standard size. To produce this result all that it is necessary to do is to loosen the plates 13 by turning the knobs 21 and respacing the plates apart around the type cylinder 9 in accordance with the size of the bag to be printed. If a large size bag is to be printed only one type plate is necessary on the cylinder, one impression being given during each revolution of the roll. If the bag to be made is half the size of the larger bag two type plates are arranged in the position indicated in the drawings so that two impressions are made during each revolution. If a bag a third the size of the larger bag is to be made then three type plates are arranged at an equal distance around the type cylinder, this operation being repeated until six plates are arranged around the cylinder for printing the smallest size bags. By my machine it will also be seen an even distribution of the ink is provided for which will absolutely prevent the blurring of the type and in which means are also provided for preventing the deformation of the inking rolls during the time the machine is standing idle.

What I claim as my invention is:

In a paper bag printing machine, the combination with the main frame, of a type cylinder mounted in the main frame, an ink fountain provided with an ink roller slidably supported upon the main frame, and transferring rollers interposed between the ink fountain and the type cylinder brought into engagement with the type cylinder and ink roller of the fountain by sliding the ink fountain toward the type cylinder.

SAMUEL JOHN HOLTHAM.
